(57) **CLAIM**

The ornamental design for a valve, as shown and described.

DESCRIPTION

1. Valve

1.1 is a rear elevation view of a valve having a handle shown in a first position.

1.2 is a top plan view of the valve with the handle shown in the first position.

1.3 is a bottom plan view of the valve with the handle shown in the first position.

1.4 is a left side elevation view of the valve with the handle shown in the first position.

1.5 is a front elevation view of the valve with the handle shown in the first position.

1.6 is a top, front, right side perspective view of the valve with the handle shown in an alternative second position.

1.7 is a top, front, right side perspective view of the valve with the handle shown in the first position.

The broken lines shown in the drawings represent unclaimed portions of the valve and form no part of the claimed design.
